UNITED STATES PATENT OFFICE.

JOHN SCHULDE, OF ST. LOUIS, MISSOURI, ASSIGNOR TO HARRY L. HUSSMANN
REFRIGERATOR & SUPPLY COMPANY, OF ST. LOUIS, MISSOURI, A CORPORATION
OF MISSOURI.

COUNTER REFRIGERATOR.

Application filed September 29, 1919. Serial No. 327,150.

To all whom it may concern:

Be it known that I, JOHN SCHULDE, a citizen of the United States, and residing at St. Louis, Missouri, have invented a new and 5 useful Improvement in Counter Refrigerators, of which the following is a specification.

This invention relates to refrigerators, and more particularly to counter or show case 10 refrigerators.

In counter or show case refrigerators, the goods are placed in a refrigerator compartment which is elongated to provide a counter or show case, being provided for that purpose with glass panels at one or more sides, and also at the top. In such a refrigerator, the refrigerant should be out of sight and should not obscure the view of the goods; accordingly, the refrigerating unit employed is 15 placed at one end of the refrigerator compartment. This, however, requires that the unit be of a high capacity so as to cause considerable reduction of temperature and moreover this unit should be arranged so as not 20 to obstruct but rather promote the circulation of a current of refrigerated air along and through the refrigerator compartments.

One of the objects of this invention, therefore, is to provide a refrigerator, which is 30 constructed so as to not only obtain the greatest refrigerating action, but also to permit the circulation of air in the refrigerator compartment.

Another object is to provide a refrigerating unit, which is simple in construction, effective in its action, easily kept in repair, and cheap to manufacture.

Further objects will appear from the detail description taken in connection with the 40 accompanying drawing, in which:

Figure 1 is a longitudinal vertical section of a refrigerator embodying this invention;

Figure 2 is a detail plan view of the drip receivers;

Figure 3 is an enlarged section on the line 3—3, Figure 1;

Figure 4 is an enlarged section on the line 4—4, Figure 3; and

Figure 5 is a detail of Figure 3.

Referring to the accompanying drawing, the refrigerator comprises an oblong structure adapted to provide an oblong refrigerator compartment, the walls and base of which are suitably packed with insulating

material as shown at 1, the inside being also 55 preferably lined with metal. The top is closed with glass panels 2, which are in spaced relation to provide heat insulating space therebetween, while the sides are also provided with glass panels of duplex construction so as to provide air insulation between the panes. Along one side, the panels are formed in doors 3 to render the interior of the refrigerator compartment accessible. Arranged in the refrigerator compartment 60 are shelves 4 and 5, the shelves 4 being supported by suitable brackets 6 formed on the inside of the refrigerator compartment, while the shelves 5 are supported near the bottom of the refrigerator compartment in 70 a manner hereinafter to be described.

Formed in any suitable position, and in this particular embodiment, at one end of the refrigerator is an opening closed by a closure 10 which is also suitably insulated 75 and is hinged at one end and provided at its other end with a hand hold 11. It will be noted that at this point the side walls 12 of the refrigerator are solid and that the sides, as well as the bottom and top, are thoroughly 80 packed with insulating material. Arranged below the top and projecting into the opening, completely around its perimeter is a ledge 13 which is suitably secured to the side walls of the refrigerator.

The refrigerating unit is constructed of sheet metal and comprises a header 14, having opening therefrom a central leg 15 and outside legs 16 arranged around the central leg. All of these legs contract downwardly 90 and the header is also somewhat contracted at its lower end as shown at 17 to form a hopper-like structure. The outside legs 16 are arranged in pairs and each pair is connected by a yoke 18. The bottoms of the 95 yokes, as well as the bottom of the leg 15 are, however, open, but the bottoms of the yokes are partially closed by strips 19 and by projections 20 of the central leg 15 attached to the strip, while the strip 21 closes the central leg 15 and firmly connects the bottoms of the legs.

The header 14 has formed thereon a ledge 22 provided with an extending rim 23 whereby the header and its outside legs may 105 be placed in position through the top opening and be positioned on and by the ledge 13. After the header is thus in position, it

may be firmly secured by a rim 24 suitably secured to the side walls of the refrigerating body.

The header is provided near its top with 5 an opening 25 forming a port arranged transversely of the refrigerating chamber. There is a port on each side opening to the refrigerator compartment, one port opening to the inside of the refrigerator compartment, while the other opens near the end wall. In order to shield these ports, there is provided for each port a canopy 26 of channel form which is apertured along its web at 27 and along its lower flange as 10 shown at 28. There is also preferably provided for each port a screen 29, this screen being placed between the canopy and its port; it is only absolutely necessary to place this screen on the inside port, i. e., the port 15 opening to the storage space, although the opposite port may also be provided with such a screen.

Arranged in the bottom of the refrigerator is a drip receiver and this drip receiver 25 comprises a series of elements, namely a series of primary drip receivers 30 placed directly beneath the header and its outside legs so as to receive the drippings therefrom, and these primary elements are detachably connected by a bridge 31 having upper inclined faces and having side flanges extending into the receivers, it being noted that these receivers are in spaced relation so as to provide an air space therebetween and 30 that they are supported on brackets 32 to raise them above the floor of the refrigerant chamber. It will be further noted that each primary drip receiver has an inwardly extending wall 33 so as to provide an air space 35 and provide an overhanging portion. Each of these overhanging portions is provided with a discharge nipple 34.

Arranged in lateral spaced relation along the bottom of the refrigerant chamber and 40 supported above the bottom on brackets are a pair of secondary drip receivers 36. Each of these secondary drip receivers is formed to provide a ledge 37 of maximum height and sloping tops 38 inclined downwardly 45 towards the center of the refrigerator. On one corner of each secondary drip receiver is a neck 39 into which a nipple 34, also on the corresponding corner of a primary drip receiver, extends. The other end of each 50 secondary drip receiving element is formed to provide an open trough 40 provided with a riser 41 discharging into a common outlet 42 which has a trap-forming pipe connection 43 discharging to the drain 44.

60 It will be noted that the drip receivers are all constructed of sheet metal and that the secondary drip receivers provide a ledge 37 for the shelves 5 in the bottom of the refrigerator chamber.

65 The header and its leg connections are

filled with a mixture of salt and ice, this mixture packing into the legs and their yokes on account of the contracted structure thereof. The canopies 26, however, prevent packing of the mixture adjacent the ports 70 25 and, therefore, provide air chambers adjacent these ports. If any small particles of ice and salt should enter these air chambers formed by the canopies, these particles will drop through and be discarded by the apertures 28. In order to provide additional protection, especially on the side where the goods are displayed, the screen 29 positively prevents the salt from being discharged on to the goods. 75

80 As the freezing mixture melts, it will drip into the receivers 30 until the same overflow through the nipples 34 into the receivers 36. As the receivers 36 overflow, the drippings will pass through the risers 41 85 into the common discharge 42 and hence by the trap 43 to the drain 44. The receivers will, therefore, become very cool, and as a mixture of salt and ice will produce a temperature very much below freezing 90 point, even the drippings in the receivers will be below freezing point.

95 Where a mixture of salt and ice is used, the mixture will, of course, remain in a solid condition and the lumps of the salt and ice will provide sufficient space so that air can pass through the header from one port to the other. Accordingly, the warmer air near the top or roof of the refrigerator compartment will enter the port on the 100 right side, Figure 1, of the header, will pass therethrough in direct contact with the freezing mixture and will pass out through the other port on the opposite side and near the end wall. The air will now drop, as 105 shown in the direction of the arrows, and will pass through the air passable lower end of the freezing mixture container and on account of the staggered relation of the legs, will come in contact with all of them and 110 become still colder.

115 The drip receivers being very cold will still further cool the air and on account of the spaced relation of the elements, the chilled air will pass therebetween and therealong as noted by the direction of the arrows. The chilled air will, therefore, travel along the lower side of the refrigerator chamber and as it reaches the lower end, it will rise and pass along the roof back to the ports 120 in the header.

125 It will, therefore, be seen that this invention accomplishes its objects. With a structure as shown and described, not only are low temperatures obtainable, but by circulation of the air throughout the refrigerator compartment, a low temperature may be obtained in every part of that compartment with a small space allowed for the refrigerating unit; accordingly, the storage and dis- 130

play space may be increased to a maximum. Furthermore, all parts are readily removable and can be readily be flushed with water whenever it is desired to clean the 5 refrigerator, although on account of the construction, such clogging will be reduced to a minimum.

It will be noted that in the counter refrigerator embodying this invention the elongated show-case provided with transparent panels has mounted at one end thereof a refrigerant container adapted to receive a freezing mixture. This container is constructed and arranged (in the particular 10 embodiment shown, by perforation of the front and back walls at the upper end of the container) to provide a top passage over the freezing mixture in the top of the container, while the arrangement is also such 15 as to provide passages along the back and bottom of the container connecting with the top passage, in order to induce a flow of air through the top passage and down the back passage. The container as well as the drip 20 pan is also adapted and positioned to cause a current of air to circulate in a path from the bottom of the container along the bottom of the show case and in a return path along the top of the show case into the top 25 of the container. This arrangement not only results in keeping the entire show case cool but by directing the current of air along the show case instead of transversely thereto, clouding of the glass panels is avoided. Furthermore any moisture or volatile 30 matter passes over the freezing mixture so as to become deposited therein and on the walls of the container so that the air is maintained dry and odorless.

40 It is obvious that various changes may be made in the details of construction without departing from the spirit of this invention; it is, therefore, to be understood that this invention is not to be limited to the specific 45 construction shown and described.

Having thus described the invention, what is claimed is:

1. In a refrigerator having a refrigerator compartment, a refrigerating unit mounted 50 in the compartment and comprising, a freezing mixture container having ports in communication with the compartment, adapted to permit air circulation through the container and in direct contact with the freezing mixture therein, canopies overhanging said ports inside of said container, and a screen for said ports.

2. In a refrigerator having a refrigerator compartment, a refrigerating unit mounted 55 in the compartment comprising, a header having legs opening therefrom and arranged in staggered relation.

3. In a refrigerator having a refrigerator compartment, a refrigerating unit mounted 60 in the compartment comprising, a header

having legs opening therefrom, including a central leg and lateral legs joined by a brace at their lower ends.

4. In a refrigerator having a refrigerator compartment, a refrigerating unit mounted 70 in the compartment comprising, a header having legs opening therefrom, including a central leg, and pairs of legs arranged around said central leg, the legs of a pair being joined at their lower ends. 75

5. In a refrigerator having a refrigerator compartment, a refrigerating unit mounted in the compartment and comprising, a laterally divided freezing mixture container, and a laterally divided brine receiver arranged 80 below said container.

6. A counter refrigerator comprising, an elongated show-case provided with transparent panels, a refrigerant container adapted to receive a freezing mixture and 85 mounted at one end of said show-case, said container being constructed and arranged to provide a top passage over the freezing mixture in the top thereof and to provide passages along its back and bottom connecting with said top passage, in order to induce a flow of air through said top passage in contact with the freezing mixture and down said back passage, said container being adapted and positioned to cause a current 90 of air to circulate in a path from the bottom of said container along the bottom of the show-case and in a return path along the top of the show-case into the top of said container. 95

7. A counter refrigerator comprising, an elongated show-case provided with transparent panels, a refrigerant container adapted to receive a freezing mixture and mounted at one end of said show-case, said 100 container being constructed and arranged to provide a top passage over the freezing mixture in the top thereof and to provide passages along its back and bottom connecting with said top passage, in order to induce a flow of air through said top passage in contact with the freezing mixture and down said back passage, and a drip pan extending along the bottom of the show-case beyond said container and adapted to receive brine therefrom, said container and said pan being adapted and positioned to cause a current of air to circulate in a path from the bottom of said container along the bottom of the show-case and in a return path along the top of the show-case into the top of said container. 110

8. A counter refrigerator comprising, an elongated show-case provided with transparent panels, a refrigerant container adapted to receive a freezing mixture and mounted at one end of said show-case, said 115 container having front and back walls which are perforated at the upper end of said container to provide a top passage over 120

- the freezing mixture in the top thereof, said container being constructed and arranged to provide passages along the back and bottom connecting with said top passage, in order to induce a flow of air through said top passage and down said back passage, said container being adapted and positioned to cause a current of air to circulate in a path from the bottom of said container along the bottom of the show case and in a return path along the top of the show case into the top of said container.
9. A counter refrigerator comprising, an elongated show-case provided with transparent panels, a refrigerant container adapted to receive a freezing mixture and mounted at one end of said show case, said container having front and back walls which are perforated at the upper end of said container to provide a top passage over the freezing mixture in the top thereof, and guards for said perforations, said container being constructed and arranged to provide passages along the back and bottom connecting with said top passage, in order to induce a flow of air through said top passage and down said back passage, said container being adapted and positioned to cause a current of air to circulate in a path from the bottom of said container along the bottom of the show-case and in a return path along the top of the show-case into the top of said container.
10. A counter refrigerator comprising, an elongated show-case provided with transparent panels, a refrigerant container adapted to receive a freezing mixture and mounted at one end of said show-case, said container comprising a header having depending legs opening therefrom, the walls of said header being perforated to provide a top passage over the freezing mixture in the top thereof, said container being constructed and arranged to provide passages along its back and bottom connecting with said top passage, in order to induce a flow of air through said top passage and down said back passage, said container being adapted and positioned to cause a current of air to circulate in a path from the bottom of said container along the bottom of the show-case and in a return path along the top of the show-case into the top of said container.

In testimony whereof I affix my signature this 30th day of July, 1919.

JOHN SCHULDE.
